RADIO-FREQUENCY HEATING SYSTEM

George H. Brown, Princeton, N. J., assignor to
 Radio Corporation of America, a corporation
 of Delaware

Application September 1, 1949, Serial No. 113,581

12 Claims. (Cl. 219—47)

1

This invention relates to high frequency heating apparatus, and more particularly to a system for coupling to a common pair of dielectric heating electrodes two sources of high frequency energy which must be independent of each other.

It is oftentimes desirable, in the process of radio frequency heating of dielectric materials, to apply large amounts of radio frequency power to the applicator electrodes. This is especially desirable in cases where long bar electrodes or a long press is used and it is desired to heat treat a thick material or a large amount of materials quickly. For supplying the required increased power, the coupling of a second generator to the electrodes is desirable. However, this poses a problem since the connection to the electrodes must be made such that while both generators supply power to the electrodes, each generator must be isolated from the other to prevent undesirable interactions.

It is the primary object of my present invention to provide an improved system of high frequency heating which permits connection of two radio frequency generators to a common pair of heating electrodes while maintaining the generators isolated from each other.

In the radio frequency heating of dielectric materials, where a long bar electrode or a long press is used, in view of the electrode length, difficulty is experienced in obtaining uniform heating along the length of the bar electrode or press. This results from the presence of standing waves which occur along the electrodes. To overcome the effect of the standing waves and to equalize the heating along the electrode, it has been customary to use inductive loading stubs which are placed along the electrode length and serve to equalize the voltage along the length of the electrode (see, for example, the Bierwirth Patent No. 2,308,043, granted on June 12, 1943).

It is a further object of my present invention to provide an improved system of high frequency heating which provides substantially uniform heating along long bar electrodes without requiring loading stubs.

These and further objects are achieved in my invention by coupling one oscillator to the opposite ends of a bar electrode so that the voltages applied by it to the two electrode ends are in phase and coupling a second oscillator to the same two ends of the bar electrode so that the voltages applied by it to the two electrode ends are in phase opposition. An effective bridge structure is formed by the transmission lines coupling the bar electrode ends to the generators,

each generator being placed at opposite diagonals of the bridge and the bar electrode being connected between the remaining two bridge diagonals. The generators are thus effectively isolated from each other. The heating effect generated along the bar electrode is substantially uniform. The frequencies at which the two generators oscillate need not be the same or synchronized.

10 The novel features of the invention, as well as the invention itself, both as to its organization and method of operation, will best be understood from the following description when read in connection with the accompanying drawings in which similar functioning parts are given the same reference numerals and in which Figures 1 through 4 are schematic diagrams of various embodiments of my invention showing systems for connecting two radio frequency generators to a pair of bar electrodes.

15 Referring to Figure 1, there is shown a bar or sealing electrode 10 and a ground plate 12 which are used to apply radio frequency heat to a dielectric load 14. A radio frequency generator 16 which is grounded on one side and which oscillates at a frequency f_1 is coupled to the opposite ends of the bar electrode 10 which terminate its longer axis. The coupling means is a pair of transmission lines 18, 20. The length of one of the transmission lines 18 between the radio frequency generator 16 and one end of the bar electrode is

$$m \frac{\lambda_1}{4} + \frac{\lambda_1}{2}$$

20 where m is any even integer and λ_1 is the wavelength at the frequency f_1 of the generator. The length of the other transmission line 20 between the radio frequency generator 16 and the other end of the bar electrode 10 is

$$m \frac{\lambda_1}{4}$$

25 Voltages are therefore applied to the two ends of the electrode 10 from the generator 16 by means of two transmission lines 18, 20 whose electrical impedance is the same but whose length always differs by a half wavelength. The voltages applied to both ends of the bar electrode 10 are therefore always out of phase.

30 A radio frequency generator 22 which oscillates at a frequency f_2 also has one side of its output grounded and has the other side of its output connected to the same two opposite ends of the bar electrode 10 to which the generator 16 is

connected. The transmission lines 24, 26 between the generator 22 and the bar electrode 10 are each equal in length to

$$\frac{n\lambda_2}{4}$$

where n is any odd integer and λ_2 is the wavelength at the frequency f_2 . Therefore, the voltages which are applied to both ends of the bar electrode 10 from the radio frequency generator 22 are applied by means of two transmission line sections 24, 26 which are always equal in length, and therefore these voltages are always in phase.

Now

$$V_1 = \sqrt{2}E_1 \cos\left(\frac{2\pi x}{\lambda_1}\right) \sin(\omega_1 t) \quad (1)$$

and

$$V_2 = \sqrt{2}E_2 \sin\left(\frac{2\pi x}{\lambda_2}\right) \sin(\omega_2 t) \quad (2)$$

Where V_1 and V_2 are the instantaneous voltages applied by the respective radio frequency generators 16, 22 at any point at a distance X from the center of the bar electrode towards either end, and E_1 and E_2 are the root mean square potentials which occur at that point.

The instantaneous power density obtained at the point x from the generator 16 with generator 22 shut down, is

$$\begin{aligned} \sigma V_1^2 &= 2\sigma E_1^2 \cos^2\left(\frac{2\pi x}{\lambda_1}\right) \sin^2(\omega_1 t) \\ &= 2\sigma E_1^2 \cos^2\left(\frac{2\pi x}{\lambda_1}\right) \left[\frac{1 - \cos(2\omega_1 t)}{2}\right] \\ &= \sigma E_1^2 \cos^2\left(\frac{2\pi x}{\lambda_1}\right) - \sigma E_1^2 \cos^2\left(\frac{2\pi x}{\lambda_1}\right) \cos(2\omega_1 t) \end{aligned} \quad (3)$$

where σ is the bar electrode conductivity.

Now, if σV_1^2 is averaged over one complete cycle of the voltage at frequency f_1 , the second term of Equation 3 averages to zero, leaving the first term unchanged. Thus, the average power P_1 in the dielectric load 14 at distance X may be expressed as

$$P_1 = \sigma E_1^2 \cos^2\left(\frac{2\pi x}{\lambda_1}\right) \quad (4)$$

If the generator 16 is now shut down and the generator 22 is delivering power, then it can similarly be shown that P_2 (average power in the dielectric 14 at distance X) may be expressed as

$$P_2 = \sigma E_2^2 \cos^2\left(\frac{2\pi x}{\lambda_2}\right) \quad (5)$$

P_1 and P_2 cannot be directly added together without an examination of their basic relations. With both generators running, the instantaneous power density total is

$$\begin{aligned} \sigma(V_1 + V_2)^2 &= \sigma \left[\sqrt{2}E_1 \cos\left(\frac{2\pi x}{\lambda_1}\right) \sin(\omega_1 t) + \sqrt{2}E_2 \sin\left(\frac{2\pi x}{\lambda_2}\right) \sin(\omega_2 t) \right]^2 \\ &= 2\sigma \left[E_1^2 \cos^2\left(\frac{2\pi x}{\lambda_1}\right) \sin^2(\omega_1 t) + E_2^2 \sin^2\left(\frac{2\pi x}{\lambda_2}\right) \sin^2(\omega_2 t) + \right. \\ &\quad \left. 2E_1 E_2 \cos\left(\frac{2\pi x}{\lambda_1}\right) \sin\left(\frac{2\pi x}{\lambda_2}\right) \sin(\omega_1 t) \sin(\omega_2 t) \right] \end{aligned} \quad (6)$$

The average of the first term of Equation 6 is

$$\frac{E_1^2}{2} \cos^2\left(\frac{2\pi x}{\lambda_1}\right)$$

The average of the second term of Equation 6 is

$$\frac{E_2^2}{2} \sin^2\left(\frac{2\pi x}{\lambda_2}\right)$$

The average of the third term of Equation 6 comes from the average of the product $\sin(\omega_1 t) \sin(\omega_2 t) \sin \omega_1 t \sin \omega_2 t = \frac{1}{2} \cos(\omega_1 - \omega_2)t - \frac{1}{2} \cos(\omega_1 + \omega_2)t$.

The average of either term is zero over an interval of time. Hence, the average power density is

$$\sigma E_1^2 \cos^2\left(\frac{2\pi x}{\lambda_1}\right) + \sigma E_2^2 \sin^2\left(\frac{2\pi x}{\lambda_2}\right) \quad (7)$$

Now, if E_1 and E_2 are made equal, then the total average power density is

$$\sigma E_1^2 \left[\cos^2\left(\frac{2\pi x}{\lambda_1}\right) + \sin^2\left(\frac{2\pi x}{\lambda_2}\right) \right] \quad (8)$$

When λ_1 is close to λ_2 ($f_1 \approx f_2$) we may make use of the relation $\cos^2 \theta + \sin^2 \theta = 1$ in Equation 8. Then the total average power density = σE_1^2 . (9)

In finding the average of the product $\sin(\omega_1 t) \sin(\omega_2 t)$ to be zero, it was assumed that $\omega_1 \neq \omega_2$.

If $\omega_1 = \omega_2$

then

$$\begin{aligned} \sin \omega_1 t \sin \omega_2 t &= \frac{1}{2} \cos(\omega_1 - \omega_2)t - \frac{1}{2} \cos(\omega_1 + \omega_2)t \\ &= \frac{1}{2} - \frac{1}{2} \cos(2\omega_1 t) \end{aligned}$$

The latter term only in this equation averages to zero and the total average power density in this instance becomes

$$\begin{aligned} &= \sigma E_1^2 \cos^2\left(\frac{2\pi x}{\lambda_1}\right) + \sigma E_2^2 \sin^2\left(\frac{2\pi x}{\lambda_1}\right) + \\ &\quad \sigma E_1 E_2 \cos\left(\frac{2\pi x}{\lambda_1}\right) \sin\left(\frac{2\pi x}{\lambda_1}\right) \end{aligned} \quad (10)$$

and if $E_1 = E_2$, Equation 10 becomes

$$\begin{aligned} &\sigma E_1^2 \left[1 + \cos\left(\frac{2\pi x}{\lambda_1}\right) \sin\left(\frac{2\pi x}{\lambda_1}\right) \right] = \\ &\quad \sigma E_1^2 \left[1 + \frac{1}{2} \sin\left(\frac{4\pi x}{\lambda_1}\right) \right] \end{aligned} \quad (11)$$

The sine term in Equation 11 is undesirable and can be eliminated by phasing the two voltages 90 degrees apart, in which event the product

$$\begin{aligned} \sin(\omega_1 t) \sin(\omega_2 t + 90^\circ) &= \sin \omega_1 t \sin(\omega_1 t + 90^\circ) \\ &= \sin \omega_1 t \cos \omega_1 t \end{aligned}$$

which averages to zero.

In the operation of the apparatus of my invention, therefore, the generators 16 and 22 are operated so that equal voltages are applied to the bar electrode 10 and the frequencies f_1 and f_2 are substantially close. If f_1 and f_2 are the same frequency, then care must be taken to shift the voltage applied by one of the generators 90 degrees with respect to the voltage applied by the other of the generators in order to eliminate the undesirable cross product term.

Now, assume that Δf is the difference in frequency between f_1 and f_2 , so that $f_2 = f_1 + \Delta f$. I have found that if the total bar electrode length does not exceed one half wavelength, then

$$\frac{\Delta f}{f_1}$$

may be as large as 0.1 and a power density varia-

tion of only ± 5 percent is obtained along the electrode. If

$$\frac{\Delta f}{f_1}$$

is 0.02 or less, then the total bar electrode length may be over one wavelength and a variation in power density of only ± 5 percent is obtained. If

$$\frac{\Delta f}{f_1} \leq 0.01$$

then the total press length may be over two wavelengths long and a power density variation of only ± 5 percent is obtained.

Although standing waves exist along the bar electrode for each generator, they serve to compensate for each other and provide substantially uniform dielectric heating along the bar electrode. The voltage from either of the generators will not interfere with the other since the transmission lines connecting the generators to the bar electrode ends form a balanced bridge with the generators being positioned at two opposite diagonals and the bar electrode being connected between the remaining two opposite diagonals.

Figure 2 is a schematic diagram of another embodiment of my invention. A line balance converter 28, such as is shown and claimed in my copending application, Serial Number 573,217, filed January 17, 1945 for Line Balance Converters, now Patent No. 2,517,968, issued August 8, 1950, is utilized to provide equal out-of-phase voltages at the bar electrode ends from the grounded or unbalanced generator 22. The in-phase voltages at the bar electrode ends are provided by the generator 16 which is connected to the ends of the bar electrode by two transmission lines 30, 32 having a wavelength which is an odd multiple of one quarter wavelength at the frequency f_1 .

The theory of operation of the line balance converter 28 is briefly as follows: Current provided by the generator 22, which is connected to the line balance converter 28 goes up through the inner conductor 56 of an input coaxial line 58. This current cannot flow down the outside of the outer conductor of the central coaxial line 60 because of the fact that a high impedance is presented by the short-circuited quarter wave section to such flow. This section is made a quarter wavelength long at the operating frequency of the generator 22. The current must therefore flow down the inside of the outer conductor of the central coaxial line 60 to ground. This induces an equal and opposite current on the inner conductor of the coaxial line 60. In view of the connection of this inner conductor, by means of equal length transmission line sections 34, 36, to the opposite ends of the bar electrode, equal and oppositely phased voltages are caused to exist at the bar electrode ends. The two generators 16, 22 are isolated from each other by virtue of the bridge formed by the transmission lines.

Figure 3 is a schematic diagram illustrating another method of connecting two generators 16, 22a to the bar electrode 10 so that they are isolated from each other and they provide substantially uniform heating along the bar electrode. The generator 16, oscillating at the frequency f_1 is connected to the ends of the bar electrode through two transmission lines of equal length to provide in-phase voltages at the ends of the bar electrode. These transmission lines are each

in length, or an odd multiple of one quarter wavelength at the frequency f_1 . Out of phase voltages are provided at the ends of the bar electrode by the output stage 35 of the other generator 22a.

This output stage 34 is readily recognized as a pair of push-pull connected tubes which are coupled to the primary winding of an output transformer 38. The ends of the center tapped output transformer secondary winding 40 are then coupled to the ends of the bar electrode through two transmission lines 34, 36, each of which is half wavelength long at the frequency f_2 of the generator 22a. Isolation of the generators is provided by the balanced bridge formed by the transmission lines used for coupling.

Figure 4 is a schematic diagram of still another and preferred embodiment of my invention which makes use of a wideband, balancing radio frequency network 42 of the type described in detail with reference to Fig. 2 of and claimed in my Patent No. 2,454,907, for a "Radio Frequency Network." The generator 16, oscillating at the frequency f_1 is coupled at terminal A to an input coaxial line 44. The generator 22, oscillating at a frequency f_2 is coupled to another input coaxial line 46 at the terminal B. The inner conductor of the co-axial line 46 is connected to the outer conductor of the coaxial line 44 at a point 48. A portion of the coaxial line 44 is surrounded by a coaxial sleeve 50 of electrically conductive material. The sleeve 50 is connected at one end to the outer conductor of the coaxial line 44. The end of the coaxial line 44 remote from the terminal A is provided with a slot 52 in its outer conductor extending diametrically across the line and longitudinally down to the point 54. The inner conductor of the coaxial line 44 passes through the length of the slot 52 and is connected to the outer conductor of the coaxial line at the free end and at one side of the slot 52. The ends of the bar electrode are connected to the opposite sides of the slot through two equal length transmission lines 54 and 56.

The slot 52 extends longitudinally down the line section one quarter wavelength at the frequency f_1 of operation of generator 16. When current at this frequency is supplied to the coaxial line 44 by the generator 16 coupled to terminal A, the instantaneous current flow is over the inner conductor of the line to the end of the outer conductor at the side of the slot 52. The two parts of the outer conductor of line 44 which are separated by the slot 52 cooperate to act as a quarter wavelength line short circuited at the point 54. This presents a substantially infinite impedance between the two slotted ends of the outer conductor of the line 44 and effectively prevents any of the current from the inner conductor from flowing down the outer conductor. Thus a current I flows along the line from terminal A and into one end of the bar electrode.

This current I flowing along the inner conductor of the coaxial line 44 from the terminal A is balanced by an equal and opposite current returning down the inside of the outer conductor of the coaxial line 44. This current flows from the other end of the bar electrode to the upper slotted end of the outer conductor of the line 44. Owing to the high impedance across the open end of the slot 52, all of the returning current flows down inside the upper portion of the outer conductor of the line section 44 below the slot 52. Thus, the opposite ends of the bar elec-

trode are energized in phase opposition by the generator coupled to the terminal A.

The outer conductor of the line section 44 cooperates with the sleeve 50 to function as a coaxial line section short circuited at the end near the terminal A. Current from the generator 22 coupled to terminal B is applied to this line section at the point 48. This current induces a voltage along the outside of the outer conductor of the line section 44 by autotransformer action. The voltage to ground from both arms of the slotted, outer conductor is the same. Thus, the voltage between the slotted ends of the outer conductor is zero, and no current is induced in the coaxial line 44 by the generator coupled to the terminal B.

Since the two ends of the outer conductor of the line 44 are at the same potential with respect to ground, the voltages at the two ends of the bar electrode coupled thereto by the two equal length transmission lines are also at the same potential. These voltages are in phase with each other. None of the current from the terminal B flows on the outside of the outer conductor of that portion of the line 44 within sleeve 50, so no current is induced in the generator coupled to the terminal A.

The radio frequency network 42 thus provides a means for applying in-phase voltages from one generator and out-of-phase voltages from a second generator which are applied to the ends of a bar electrode, and yet the two generators are isolated from one another because of the bridge action of the radio frequency network. In my co-pending application for Radio Transmitters, application Serial Number 52,635, filed October 4, 1948, now Patent 2,602,887, issued July 8, 1952, there is described and claimed a system for feeding two transmitters to an absorber element and a common load using the above described radio frequency network. Therein, it is shown that the output from the two generators is added in a load and neutralized in an absorber element. In the instant application, the radio frequency network is used to supply a single load (namely the bar electrode which is connected across its output) simultaneously with in-phase and out of phase voltages.

From the foregoing description, it will be readily apparent that I have provided an improved system or apparatus for coupling two generators to a common pair of electrodes in order to provide substantially uniform heating along the electrode and to maintain the generators isolated from each other. Although several embodiments have been shown and described, it should be apparent that many changes may be made in the several embodiments herein disclosed, and that many other embodiments are possible, all within the spirit and scope of my invention. Therefore, I desire that the foregoing description shall be taken as illustrative and not as limiting.

I claim as my invention:

1. A system for radio frequency heating comprising a radio frequency source of in-phase voltages, a radio frequency source of substantially 180 degree out-of-phase voltages, a bar electrode, and bridge network means coupling said sources to the opposite ends of said bar electrode to provide substantially uniform heating therealong and isolating one of said radio frequency sources from the other.

2. A system for coupling two sources of radio frequency heating energy to a bar electrode for dielectric heating comprising a balanced bridge

circuit having four diagonals, said bar electrode being coupled between two opposite diagonals of said bridge circuit, each of said two sources of radio frequency heating energy being coupled to 5 each of the other two opposite diagonals, and 180 degree voltage phase shift means in one of the arms of said bridge.

3. A system for coupling two sources of radio frequency heating energy to a bar electrode comprising a balanced bridge circuit having four diagonals, said bar electrode being coupled between two opposite diagonals of said bridge circuit, one of said two sources of radio frequency heating energy being coupled to one of the other diagonals 15 of said bridge to provide in-phase voltages at said bar electrode opposite ends, and means in said other bridge diagonal coupled to the other of said two sources of radio frequency heating energy to provide substantially 180 degree out-of-phase voltages at said bar electrode opposite ends.

4. The system recited in claim 2 wherein said means in said bridge diagonal coupled to the other of said two sources of radio frequency energy to provide said out-of-phase voltages at said bar electrode opposite ends comprises a push-pull output transformer.

5. The system recited in claim 2 wherein said means in said bridge diagonal coupled to the other of said two sources of radio frequency energy to provide said out-of-phase voltages at said bar electrode opposite ends comprises a line balance converter.

6. A system for coupling two sources of radio frequency heating energy to a bar electrode comprising a first pair of transmission lines connected together at one end and coupled at said one end to one of said two sources, the other ends of said first pair of transmission lines being coupled to the opposite ends of said bar electrode, each of said first pair of transmission lines being an odd multiple of a quarter wavelength long at the frequency of operation of said one source to provide in-phase voltages at said bar electrode opposite ends, and a second pair of transmission lines connected together at one end and coupled to the other of said two sources at said end, the other ends of said second pair of transmission lines being coupled to said opposite ends of said bar electrodes, one of said second pair of transmission lines being an even multiple of a quarter wavelength long at the frequency of said other of said two sources, the other of said second pair of transmission lines being one half wavelength longer than said one of said second pair of transmission lines to provide out-of-phase voltages at said bar electrode opposite ends whereby said two sources are isolated from each other and substantially uniform heating is provided along the bar electrode length.

7. A system for coupling two sources of radio frequency heating energy to a bar electrode comprising a first pair of transmission lines connected together at one end and coupled at said one end to one of said two sources, the other ends of said first pair of transmission lines being coupled to the opposite ends of said bar electrode, each of said first pair of transmission lines being an odd multiple of a quarter wavelength long at the frequency of operation of said one source to provide in-phase voltages at said bar electrode opposite ends, a line balance converter for converting an unbalanced input to a balanced output, said other source of radio frequency heating energy being coupled to said line balance converter input, a second pair of transmission lines having a length 70 equal to one half wavelength at the frequency of

said other source, said second pair of transmission lines being coupled from said line balance converter output to said bar electrode opposite ends to provide out-of-phase voltages at said bar electrode opposite ends whereby said two sources of radio frequency heating energy are isolated from each other and substantially uniform heating is provided along the bar electrode length.

8. A system for providing substantially uniform radio frequency heating along a bar electrode comprising a first radio frequency generator, a second radio frequency generator having a push-pull output, a first pair of transmission lines connected together at one end and coupled at said one end to said first radio frequency generator, 15 the other ends of said first pair of transmission lines being coupled to the opposite ends of said bar electrode, each of said first pair of transmission lines being an odd multiple of a quarter wavelength long at the frequency of operation of said first radio frequency generator, and a second pair of transmission lines coupled between the push-pull output of said second radio frequency generator and said bar electrode opposite ends, each of said second pair of transmission lines being one half wavelength long at the frequency of operation of said second radio frequency generator to provide out-of-phase voltages at said bar electrode opposite ends whereby said first and second radio frequency generators are isolated from each other and there is provided substantially uniform heating along said bar electrode.

9. A system for providing substantially uniform radio frequency heating along a bar electrode comprising a radio frequency network including a first coaxial input line, a conductive sleeve surrounding one end of said line and connected to the outer conductor of said line at a point near said end, the end portion of the outer conductor 40 of said line including a longitudinal slot, the end of the inner conductor of said line being connected to the end of the outer conductor of said line at one side only of said slot, a second coaxial input line having one conductor connected to said sleeve and the other conductor coupled to the outer conductor of said first input line within said sleeve, a first radio frequency generator coupled to said first coaxial input line, and a second radio frequency generator coupled to said 50 second coaxial input line, the opposite ends of said bar electrode being coupled between the two opposite portions of said longitudinal slot at the

portion on said line outer conductor where said inner conductor end is connected to said outer conductor end whereby said first and second radio frequency generators are isolated from each other and uniform heating is provided along said bar electrode.
